UNITED STATES PATENT OFFICE.

WILLIAM CASE, OF CHICAGO, ILLINOIS, ASSIGNOR TO THE NATIONAL
MALLEABLE CASTINGS COMPANY, OF CLEVELAND, OHIO.

SPRING-PLANK FOR CAR-TRUCKS.

SPECIFICATION forming part of Letters Patent No. 550,907, dated December 3, 1895.

Application filed March 28, 1895. Serial No. 543,440. (No model.)

To all whom it may concern:

Be it known that I, WILLIAM CASE, of Chicago, Illinois, have invented certain new and useful Improvements in Spring-Planks for 5 Car-Trucks, of which the following is a specification.

The object of my invention is to provide a simple, economical, and efficient spring-plank; and the invention consists in the features and combinations hereinafter described and claimed.

In the drawings, Figure 1 is a plan view of my improved spring-plank, looking at it from the bottom; Fig. 2, a plan view of the same, 15 looking at it from the top; Fig. 3, an enlarged transverse section taken on line 3 of Fig. 2, and Fig. 4 a side view of Fig. 3.

In constructing my improved spring-plank I use two spring-plates A, of the desired form 20 and size, formed, preferably, of malleable iron and provided with several ribs a on the bottom of the recess for the purpose of giving the plates the requisite strength to withstand ordinary working stress and also to provide 25 pockets for the reception of the connecting- rods.

I connect the spring-plates together by means of two iron rods B, having their ends 30 b bent at right angles to fit in the pockets above referred to in the lower side of the spring-plates, and I secure these rods B together, preferably in an X shape, by means 35 of a metallic clamp C, formed, preferably, in two portions and bolt or rivet them together at c.

I provide transom-columns D, U-shaped in cross-section, as shown on line 3 of Fig. 2, and reduce the size of the end d so that it will snugly fit the socket cast for it in the 40 spring-plate. These transom-columns have a flanged inner surface d', and an interior chamber which is provided with four ribs d'', that fit loosely around the bolt E that joins the transom-columns, arch-bars, and spring- 45 plate together, as hereinafter described. The upper and lower ends of the transom-columns are bored out to snugly fit the bolt and prevent any lateral motion thereon.

To securely bind all the parts of the spring- 50 plank together and with the arch-bars, I provide the upper end of the transom-column, as at d³, with a groove or slot adapted to receive the arch-bar G, and the lower surface

of the spring-plates with ribs, as at a', to form a slot or groove a'', that will receive the 55 arch-bar H. I then join these arch-bars, transom-columns, and spring-plates together by means of the bolts E, which are provided at their upper ends with a head e and at their lower ends with lock-nuts e'.

While I have described these connecting- 60 rods as round bars, I do not desire to be limited to such bars, as I contemplate using different shapes of rods in cross-section—as, for instance, T-rods or channel-shaped rods.

I claim—

1. A spring plank for car trucks composed of two metallic plates forming spring seats provided with pockets on the under side to receive connecting rods, a rod or rods connecting the spring plates together, and means for rigidly securing the plates and rod or rods together, substantially as described.

2. A spring plank for car trucks composed of two metal plates forming spring seats provided with pockets on the under side to receive connecting rods, two connecting rods provided with angular ends fitted in the pockets of the plates, and means for rigidly securing the rods and plates together, substantially as described.

3. A spring plate for car trucks composed of two metal plates forming spring seats provided with ribs on one of its surfaces forming pockets for the reception of connecting rods 85 and slots for an arch bar, transom columns removably secured to the spring plates, connecting rods fitted in the pockets of the plates, and bolts to secure the arch bars, transom column, spring plates and connecting rods 90 together, substantially as described.

4. A spring plate for car trucks composed of two metal plates forming spring seats provided with ribs on its under surface forming pockets for the reception of connecting rods 95 and slots for an arch bar, transom columns removably secured to the spring plates, substantially X-shaped connecting rods fitted in the pockets of the plates, and bolts to secure the arch bars, transom columns, spring plates 100 and connecting rods together, substantially as described.

WILLIAM CASE.
